UNITED STATES PATENT OFFICE.

ELDRIGE S. FOXWORTH, OF GLENMORA, LOUISIANA.

AEROPLANE-BOMB.

1,276,635.

Specification of Letters Patent. Patented Aug. 20, 1918.

Application filed February 2, 1918. Serial No. 215,100.

To all whom it may concern:

Be it known that I, ELDRIGE S. FOXWORTH, a citizen of the United States, residing at Glenmora, in the parish of Rapides 5 and State of Louisiana, have invented new and useful Improvements in Aeroplane-Bombs, of which the following is a specification.

This invention relates to bombs or explosive shells especially adapted to be dropped from aeroplanes and other aircraft, the bomb being of such a character that it ignites inflammable material contained within the shell of the bomb and explodes and 10 bursts the shell, scattering and spreading the burning liquid with great damage to the life and property of the enemy. The bomb, when it explodes and scatters the burning liquid, illuminates a considerable 15 territory thereby enabling a number of aeroplanes or other aircraft to more effectively attack the enemy at night time.

With the above and other objects in view, the invention consists in the novel construction, combination and arrangement of parts, 20 herein described, illustrated and claimed.

The accompanying drawing represents a vertical longitudinal section through the improved bomb.

30 The improved bomb in the preferred formation thereof comprises a tapering thin metal shell 1 larger at the bottom than at the top, the same being closed by a bottom wall 2 and a top wall 3. The upper end 35 portion of the shell, above the top wall 3 is preferably conical in shape as shown at 4 and has a ring or eye 5 at the apex thereof by which the bomb is suspended or held in the hand preparatory to dropping the same.

40 Secured to the top wall 3 and extending downwardly therefrom is a cylindrical container 6 in which is inserted an explosive or bursting charge 7 and a percussion cap 8 or the equivalent thereof. 9 designates a 45 firing plunger which is slidable through an opening in the bottom wall 2, said opening being guarded by a stuffing box 10. The plunger rod 9 extends below the bottom of the container and is provided with radiat-

50 ing arms or fingers 11 between which and the bottom of the shell are interposed compression springs 12 which hold the firing plunger normally depressed so that it does not contact with the cap in the explosive charge chamber 6. The firing plunger 9 is additionally held depressed by means of an-

other compression spring 13 which encircles the rod 9 between the bottom of the chamber 6 and a cup-shaped spray thrower 14 which is fastened to the plunger 9 and braced by a cone-shaped extension 15 on the bottom of said spray thrower. If desired a cotter pin 16 may be inserted through the firing plunger 9 against which the lower extremity of the spring 13 may bear. 17 60 65 designates a removable plug for giving access to the chamber 6 for the insertion of the bursting charge and the percussion cap.

In the use of the bomb, gasolene or other highly volatile hydrocarbon is placed in the 70 shell 1 slightly above the level of the spray thrower 14. A bursting charge is inserted in the chamber 6 and also a percussion cap so as to be struck by the plunger 9. The bomb is dropped with the large and heavier 75 end lowermost and upon striking the ground or any other object, the plunger is thrust upwardly, exploding the cap, firing the bursting charge and simultaneously a spray or portion of the gasolene or other liquid is 80 thrown across one or more openings 18 in the side of the chamber 6. This insures the ignition of the liquid and the bursting of the shell and consequently the spreading of the burning liquid throughout a consider- 85 able area.

In order to still further provide for the safety of the device, I form a hole 18 in the plunger rod 9 and in conjunction therewith, I employ a sliding locking rod 19 which 90 extends through eyes or guides 20 on the lower side of the bottom 2 of the device. The rod 19 has a laterally projecting finger piece 21 adjacent to its outer end which is adapted to be moved into and out of engagement with a retaining clasp 22 secured to the device adjacent to the bottom corner thereof. The locking rod 19 will be left in engagement with the plunger rod 9 until the bomb is to be used; then the locking rod 100 95 100 will be withdrawn from engagement with the plunger rod and secured to the clasp or keeper 22. The plunger rod 9 is now free as far as the locking rod 19 is concerned.

I claim:—

1. A bomb comprising in combination, a shell or container for inflammable liquid, a chamber in the upper part of said shell, a bursting charge in said chamber, a percussion cap therein, a plunger extending longitudinally of the shell and projecting below the bottom end thereof, means for yieldably

holding said plunger at the lower limit of its movement, said plunger being adapted to contact with said cap, and a cup-shaped spray thrower mounted upon and movable 5 with said firing plunger.

2. A bomb comprising in combination, a shell or container for inflammable liquid, a chamber in the upper part of said shell, a bursting charge in said chamber, a percus- 10 sion cap therein, a plunger extending longitudinally of the shell and projecting below

the bottom end thereof, means for yieldably holding said plunger at the lower limit of its movement, said plunger being adapted to contact with said cap, and a cup-shaped spray thrower mounted upon and movable with said firing plunger, said bursting charge chamber having an opening across 15 which the spray is thrown.

In testimony whereof I affix my signature. 20

ELDRIGE S. FOXWORTH.
